UNITED STATES PATENT OFFICE.

HENRY C. SMITH, OF BOSTON, MASSACHUSETTS, ASSIGNOR TO SMITH-WARREN COMPANY, OF BOSTON, MASSACHUSETTS, A CORPORATION OF MASSACHUSETTS.

MACHINE FOR ASSEMBLING WINDOW-FRAMES.

SPECIFICATION forming part of Letters Patent No. 745,299, dated November 24, 1903.

Application filed July 21, 1902. Serial No. 116,409. (No model.)

To all whom it may concern:

Be it known that I, HENRY COLLIER SMITH, of Boston, in the county of Suffolk and State of Massachusetts, have invented a new and useful Improvement in Machines for Assembling Window-Frames and the Like, of which the following is a specification.

The parts of a sheet-metal window-frame must be assembled with absolute accuracy, for the reason that such window-frames are ordinarily brazed at the joints, and it is practically impossible to correct any inaccuracy in construction after the frames are once set up. For this purpose I have constructed an assembling-machine which while it is especially adapted for assembling the parts of window-frames may be used with but slight modifications for assembling parts of other devices which are to be joined at an angle to each other, whether such devices are quadrilateral or not.

My invention will be understood by reference to the drawings, in which—

Figure 1 is a plan of a portion of the upper part of the track-ring, being broken away. Fig. 2 is a side elevation, the frame-clamps being omitted. Fig. 2^A is also a side elevation taken at right angles to Fig. 2. Fig. 3 is a section on line 3 3 of Fig. 4, Fig. 4 being a detail of the side clamp. Fig. 5 is a section on line 5 5 of Fig. 6, Fig. 6 being a detail of the head-clamp. Fig. 7 is a section on line 7 7 of Fig. 8, Fig. 8 being a detail of the sill-clamp. Fig. 9 is an enlarged view of the central adjusting-clamp, Fig. 10 being a section on line 10 10 of Fig. 9. Fig. 11 is an enlarged section on line 11 11 of Fig. 2. Fig. 12 is a section on line 12 12 of Fig. 1 enlarged. Fig. 13 is an enlarged view of the centrally-adjusted clamp in vertical cross-section. Fig. 14 is a view of a modification of the central adjusting-clamp, Fig. 15 being a section on line 15 15 of Fig. 14. Figs. 16 and 17 are front and side views, respectively, of a modification embodying my invention, Fig. 18 being a section on line 18 18 of Fig. 16.

I shall describe my invention as embodied in a machine for assembling four-sided sheet-metal window-frames, as it is for this purpose

the invention was primarily made, and, as shown in the drawings, the parts of the machine by means of which the several portions of the window-frame are held are capable not only of a movement about a vertical axis, but also about a horizontal axis. For this purpose these parts are mounted in a manner below described upon a platform A, having a central pin a, which, as shown, seats into the socket a' in the floor. (See Fig. 2.) The platform as constructed consists of a rectangular skeleton suitably braced by means of braces a² and provided with casters a³, attached to its under side, so as to support it and allow it to be turned in either direction with the least possible friction. B is a stationary ring mounted on this platform A, being attached thereto by angle-irons a⁴. Braces B' run from blocks b at the corners of the platform to the ring at opposite sides near the extremities of its horizontal diameter. It will thus be seen that the ring as a whole is capable of rotation about a vertical axis with the platform A. The ring is preferably T-shaped in cross-section, (see Fig. 11,) having bearing-surfaces b' b' on its inner side and opposing bearing-surfaces b² b² upon its outer side.

Within the ring B is supported the assembling mechanism proper in such a manner that it may be rotated about a horizontal axis. For this purpose I prefer to provide a carriage comprising a cross-bar C, a central support D, and two braces D' D', connecting the extremities of the cross-bar C with the extremity of the central support D, the whole forming a support for the assembling-frame. The cross-bar C has at each end and the support D has at its outer end a forked piece C', fastened thereto by set-screws c. This forked piece carries in both forks a shaft c', headed at one end c² and having a cotter-pin c³ at its other end to hold it in place. Upon this shaft is carried a spool-shaped roll c⁴, having treads which run on the bearing-surfaces b' of the ring B and flanges c⁵ which hold it from lateral movement with relation thereto. The extremity of each fork carries a stud on which is a roll c⁶, which runs on one of the

bearing-surfaces b^3 of the ring B. This cross-bar C has a socket c^7 near its middle, through which the central support D passes. The upper end of the central support D is reduced in size, as at d , so that a shoulder is formed on which the assembling-frame rests. A loop-frame c^8 connects the two parts of the cross-bar C and carries a socket c^9 to receive the upper end of the reduced portion d of the central support D. Between the sockets c^7 and c^9 is supported the assembling-frame now to be described.

E F are two castings, each of which comprises two pairs of sockets connected by a bar. The sockets of the casting E are marked E' and those of the casting F are marked F' . The bars referred to are marked E^2 and F^2 , respectively, and each is provided with a hole E^3 F^3 , through which passes the part d of the central support D. Washers e , e' , and f on d separate these various parts. These sockets E' F' are for the purpose of holding the free ends of beams G, which beams extend from the center of the assembling-frame to its four corners, where each beam is received in a socket H, attached to one of the corner-pieces K in the manner below described. Each beam G is clamped in its various sockets preferably by means like that shown in Fig. 10, which is a cross-section of one of the sockets F' and shows the wooden braces G in position therein.

F^4 is a clamping-shoe held against the brace G by means of a set-screw f' passing through an oblique portion f^2 of the socket-piece F' and engaging the corresponding oblique portion f^3 of the shoe F^4 . By this means the turning of the screw f' serves not only to clamp the brace G horizontally, but also vertically. Each socket-piece E' is provided with similar clamping means.

The sockets H, which serve to receive the outer ends of the braces G, may be provided with an ordinary set-screw or with the clamping mechanism above described by means of which to clamp the end of the brace G into the said socket. The purpose of this central socket arrangement is to enable the assembling-frame to be adjusted for window-frames of different sizes.

The corner-pieces of the machine are all made alike; but, as will be seen below, two of them are used in reverse position from the other two. They are supported by the braces G, extending from the center of the frame, and also by the side rods J J' and the end rods J^2 J^3 , these rods extending from corner to corner, giving to the frame its general rectangular character.

It will be seen that the side rods are at a slight angle with the horizontal. This is rendered necessary by reason of the reversal of the corner-pieces above referred to, which brings the opening J^4 of one corner-piece near the top of one casting and near the bottom of the next casting. One of these corner-pieces is shown detached in Fig. 12. Each com-

prises a right-angled casting K, having two bearing-surfaces k , to which the frame-clamps are attached, being also provided with a slotted portion k' , in which sits an eye h , projecting from the socket H. A bolt h' , provided with a suitable set-nut h^2 , passes down into the corner-piece K and through the eye h to hold the socket and corner-piece together. Through this opening J^4 in each piece passes one end of one of the rods J J', which rod is clamped in place by means of a set-screw j . One of these openings is shown in Fig. 12. Each corner-piece also has a sleeve J^5 to receive the end of one of the end rods J^2 J^3 . (See Fig. 1.) The rods J^2 J^3 are held in their sleeves by a set-screw j' . Each side rod is supported on the carriage C by a clamp J^5 . To each bearing-surface k of one of these corner-pieces K is attached by bolts k^2 a frame-clamp constructed to hold a portion of the frame to be assembled. These clamps differ somewhat in structure, according to the shape of that portion of the frame which each is to hold; but each is provided with means for attachment to a corner-piece, comprising an arm K' , having a bearing-surface K^2 . These clamps are shown in detail in Figs. 3 to 8, inclusive. The side clamps are shown in Figs. 3 and 4 and are constructed as follows: The side clamps are lettered L and L' . They are four in number, and the clamp portion of each is like the clamp portion of all the others. They differ only in that the arm K' projects from one side of the clamp L' and from the opposite side of the clamp L. The clamp shown in Figs. 3 and 4 is one of the clamps L' . The fixed member L^2 has a skeleton face l with suitable projections l' thereon, adapted to receive portions of the inner face of the side rails of the window-frame, and it has on its farther side a grooved surface l^2 to receive the adjustable locking member l^3 of the movable member. The movable member of the clamp comprises a clamping-piece l^4 , which is fork-shaped, the two ends l^5 of the fork being shaped to engage the opposite surface of that portion of the sash-frame which bears against the surface l of the clamp. This clamping-piece is held in place by means of a heavy bow-spring l^6 , pivoted to it at l^7 , the spring being of an irregular bow shape and having an eye at its free end, through which passes the locking member l^8 , which is threaded and has upon it a set-nut l^9 , the inner end of this locking member l^8 being adapted to slide in the groove l^2 in the part L^2 of the clamp and being adapted to be set up to adjust the spring to frames of varying thicknesses. Where the shape of the frame requires it, the fixed member L^2 may be compound in character, as indicated in Figs. 3 and 4, where a sleeve L^3 extends rearward from its face L^5 , and slides on a stud L^4 , which is connected to the arm K' . The sleeve is slotted, as at L^5 , and a pin L^6 , projecting from the stud L^4 through the slot L^5 , limits the movement of

the sleeve L³. The clamps shown in Figs. 5 and 6 are adapted to receive the head of the window-frame and are those clamps lettered M in Fig. 1. They are also alike except as 5 their attaching member K' in one case projects from one side of the clamp member and in the other case from the opposite side of the clamp member, this being a matter of convenience, however. These head-clamps 10 have parts corresponding to parts of the side clamps—namely, a skeleton face m, shaped to conform to the head-rail of the sash, a grooved surface m², locking member m³, fork-shaped clamping-piece m⁴, ends of the fork 15 m⁵, and a heavy spring m⁶, pivoted at m⁷, the locking member m³ being threaded, as described, and having a set-nut m⁸. The sill-clamps are lettered N and are similar in character to the other clamps, comprising the following parts: the skeleton face n, projections n', grooved surface n², locking member n³, clamping-piece n⁴, ends of the fork n⁵, heavy spring n⁶, pivoted at n⁷, the locking member being threaded, as before, and having a set- 25 nut n⁸. In each of these views the window-frame is shown in dotted lines, the side rails being lettered P, the head-rail being lettered P', and the sill P², and with each of these clamps it will be noted that when the frame 30 is to be released the bow-springs l⁶ m⁶ n⁶ are all turned about their pivots l⁷ m⁷ n⁷ sufficiently far to disengage the locking members from their grooves l² m² n², and each clamp is thereby loosened from its engagement with 35 the other clamp member, thus releasing the frame, which thereafter rests only upon the top wall of the projections l'. The face of the side clamps must now be pushed back to withdraw the projections l' from between the 40 projections on the side rail of the frame, and the frame may then be lifted from the machine and the parts of another frame assembled by reversing the operations. It is evident that the faces of these clamp members 45 may be altered to suit differing shapes of window-frames.

An important feature of this invention is the means for adjusting the assembling-frame to frames of different sizes. To make this 50 adjustment with the apparatus above described, the set-screws f' are loosened and also all the screws j j', thus allowing the corner-pieces to slide upon the rods J J' J² J³ and at the same time the braces G to adjust 55 themselves within their sockets E' F'. When the proper adjustment has been reached, the set-screws are again set in place and the machine is ready to take a frame of larger or smaller size, as the case may be. It is evident, however, that this adjustment can only be had within certain rather restricted limits. If a further adjustment is needed, other rods of different length may be substituted for the rods J J' J² J³.

60 I have shown in Fig. 14 another means for adjusting the braces G, each brace in this case being provided with a rack g, the racks

of two adjacent braces facing each other and all these racks engaging a pinion g', adapted to turn on the upper end of the rod D and 70 having a square projection g² to receive a wrench or key by which the parts may be adjusted when the necessary clamp-screws f' have been loosened. As an additional precaution, in this case I provide sleeves g³, connected by links g⁴ with the clamps E F, these sleeves sliding upon the cross-rod C and being held in place thereon by set-screws g⁵. I have shown in Figs. 16, 17, and 18 another means embodying my invention for supporting the assembling-frame. This means comprises a standard Q, from the top of which projects laterally an arm Q', carrying a socket Q². R is a ring which turns in bearings formed by the segments R' R². These segments are bolted together, and the ring is provided with flanges r, by which it and the segments R' R² are kept in proper relation. The segment R² carries on its under side a socket R³. The passage in this socket is 85 adapted to register with the passage in the socket Q², and the two are attached together by means of a driven pin q, which fits into both sockets. The ring R has two sockets r', diametrically opposite each other, in which 90 is supported a rod d', which has all the functions of the portion d of the central support D shown in connection with the main embodiment of my invention, and between the two sockets r' are intended to be supported 100 the central clamping mechanisms E F of the assembling-frame, the rectangular portions of the frame and their corner-pieces being located outside of the periphery of the segments R' R².

105 It is evident that this invention may be embodied in other ways, its main peculiarity being that an absolutely rectangular assembling-frame is supported not only to turn upon a vertical axis, but also upon a horizontal axis, so that all portions and all sides of the frame may be presented to the operator at a convenient place to be worked upon. It is also evident, however, that in the modification shown in Figs. 16 and 17 the frame can 110 only be turned about its horizontal axis through an angle of ninety degrees, as otherwise it will strike the standard Q, and it is also evident that its horizontal rotation about its vertical axis is also limited by reason of 115 the engagement of parts of the assembling-frame with the ring, which is not rotatable about a vertical axis.

120 What I claim as my invention is—

1. In an assembling-machine, a ring, an assembling-frame supported to turn upon a horizontal axis inside the ring, and a support for said frame located within the ring and so combined therewith that the assembling-frame carried by it will have the horizontal 125 movement aforesaid.

2. In an assembling-machine, a ring supported to turn upon a vertical axis, an assembling-frame supported to turn upon a hori-

zontal axis inside the ring, and a support for said frame located within the ring and so combined therewith that the assembling-frame carried by it will have the horizontal movement aforesaid.

5. In an assembling-machine, a ring, suitable means of support therefor, a carriage mounted within said ring to rotate about a horizontal axis and an assembling-frame 10 mounted upon said carriage.

15. In an assembling-machine a ring suitably supported to turn on a vertical axis, a carriage traveling thereon and comprising a central support, a cross-bar mounted thereon, said central support and said cross-bar carrying rolls adapted to run upon said ring, in combination with an assembling-frame 20 mounted on said carriage, as and for the purposes described.

25. In an assembling-machine a ring, a carriage traveling thereon and comprising a central support, and a cross-bar mounted thereon, said central support and said cross-bar each having at its extremity two sets of rolls, one adapted to engage with the interior surface of said ring and the other set adapted to engage the exterior surface of said ring, in combination with an assembling-frame 30 mounted on said carriage, as described.

35. In an assembling-machine of the character specified, an assembling-frame having frame-holding clamps on each of its sides, and means for supporting said frame whereby the same may turn horizontally and vertically.

40. In an assembling-machine, a rectangular frame carrying two or more frame-holding clamps along each of its sides, means for supporting the clamp-bearing sides of the frame whereby said sides may be relatively lengthened, and means for supporting said frame whereby the same may be turned on both a vertical and horizontal axis.

45. In an assembling-machine, an assembling-frame comprising a rectangular frame carrying clamps to receive the members of the article to be assembled, the length of the sides of said frame being adjustable, means for obtaining such adjustment, said frame also having a series of braces extending toward its center, and means for adjusting the length of said braces, as and for the purposes described.

50. In an assembling-machine, an assembling-frame comprising four rods forming the four sides thereof, corner-pieces joining the adjacent ends of said rods, each corner-piece carrying clamps to receive members of the article to be assembled, said corner-pieces being adjustable on said rods and each corner-piece also carrying a socket adapted to receive one end of a brace, in combination with said braces and means located near the center of said frame adapted to clamp together the ends of said braces, as and for the purposes described.

55. In an assembling-machine a quadrilateral

eral frame carrying one or more clamps at each corner to receive members of the article to be assembled, a series of braces running 70 from each corner toward the center of said frame, a series of clamps located at the center of said frame and comprising socketed pieces adapted to receive the ends of said braces and clamps to hold said braces there- 75 in, and means for supporting said frame comprising a central support passing through said socketed pieces, and means for bracing said central support, as described.

80. In an assembling-machine, a frame having corner-pieces carrying clamps for receiving the work to be assembled, braces extending from said corner-pieces toward the center of the frame, one or more sockets for receiving each brace, means for locking the 85 said braces in their respective sockets permitting of their adjustment therein, means for supporting the said frame to turn upon a horizontal and also upon a vertical axis.

85. In an assembling-machine, an adjustable rectangular frame having braces extending from its corners toward its center, means for adjusting said braces comprising socket-pieces connected together as described, each socket-piece being provided with an opening 90 at right angles to its length, and means for supporting said frame comprising a vertical ring and a carriage supported within and adapted to run about said ring, said frame being located on said carriage, whereby said 95 frame may be given movement about a horizontal axis, as described.

100. In an assembling-machine, a clamp for holding a window-frame member comprising a stationary member having a face against 105 which the window-frame member is to be clamped, and a free member comprising a clamping-face having a bow-spring pivotally connected thereto, the free end of said spring having a locking means whereby it may reach 110 over and engage the reverse side of said stationary member, as and for the purposes set forth.

115. In an assembling-machine of the character described, a rectangular adjustable frame and braces extending from the corners thereof toward the center, means for adjusting said braces comprising a rack attached to each brace, a pinion located between said racks, a central support carrying said pinion, socket-pieces forming bearings for said braces, means for clamping said braces in said socket-pieces, and means for clamping in position the said socket-pieces with relation to said frame, as and for the purposes described. 125

120. In an assembling-machine, an adjustable rectangular frame having braces extending from its corners toward its center, means for adjustably clamping said braces whereby they may become lengthened, means for adjusting the length of the sides of said frame, clamps carried by said frame to receive members of the article to be assembled, means for supporting said frame adapted to turn on 130

both a vertical and a horizontal axis, as described.

16. In an assembling-machine, an adjustable rectangular frame having braces extending from its corners toward its center, means for adjustably clamping said braces whereby they may become lengthened, means for adjusting the length of the sides of said frame, clamps carried by said frame to receive members of the article to be assembled, and means for supporting said frame comprising a carriage adapted to turn on a horizontal axis and a support for said carriage adapted to turn on a vertical axis, as described.

17. In an assembling-machine, a frame having two or more diagonally-extending brace-beams crossing each other, means for adjustably supporting and securing the beams at their intersection whereby the same may be lengthened and their direction changed relatively to one another, corner-pieces mounted or carried on the outer ends of the beams, means for adjustably connecting and securing the adjacent corner-pieces, means for removably clamping the parts of the frame to be assembled to the corner-pieces in position ready to be joined, means for revolving the carriage thus formed on a vertical axis, and means for revolving it upon a horizontal axis.

18. In an assembling-machine, a frame having two or more brace-beams crossing each other to intersect at approximately the center of the frame, corner-pieces mounted on the ends of said brace-beams, central socket-bearings for receiving said brace-beams, means for clamping the said braces within said socket-bearings whereby the same may become adjusted therein, a central shaft or pin for supporting said socket-bearings and means for clamping the work to be assembled to the corner-pieces aforesaid.

19. In an assembling-machine, a frame having two or more brace-beams extending diagonally in different directions, corner-pieces

mounted upon the ends of said brace-beams carrying clamps for receiving the work to be assembled, sockets for receiving said brace-beams at their crossing-point, means for clamping the said brace-beams within said sockets permitting of the adjustment of the braces therein, a central vertical shaft or pin support for said braces and socket members, and means for turning said frame thus supported upon a horizontal axis, substantially as described.

20. In an assembling-machine, a frame having corner-pieces carrying clamps for receiving the work to be assembled, sides connecting said corner-pieces, means whereby the said corner-pieces may be adjusted along said sides whereby the relative length of the same may be increased or diminished, and means for supporting said frame.

21. In an assembling-machine, a frame having corner-pieces carrying clamps for receiving the work to be assembled, sides connecting said corner-pieces, means whereby the said corner-pieces may be adjusted along said sides whereby the relative length of the same may be increased or diminished, and means for supporting said frame whereby the said frame may be turned upon both a pivotal and horizontal axis.

22. In an assembling-machine, a frame having corner-pieces carrying clamps for receiving the work to be assembled, sides connecting said corner-pieces, means whereby the said corner-pieces may be adjusted along said sides whereby the relative length of the same may be increased or diminished, braces extending from said corner-pieces toward the center of the frame, and means for adjustably supporting said braces whereby the length of the same may be made to accord with the relative length of the sides of the frame.

HENRY C. SMITH.
